UNITED STATES PATENT OFFICE.

MARIUS C. A. LATOUR, OF PARIS, FRANCE

AUDION OR LAMP RELAY OR AMPLIFYING APPARATUS.

1,405,523.

Specification of Letters Patent. Patented Feb. 7, 1922.

Application filed December 28, 1917. Serial No. 209,269.

To all whom it may concern:

Be it known that I, MARIUS C. A. LATOUR, a citizen of the Republic of France, residing at Paris, 10 Rue Auber, France, have invented certain new and useful Improvements in or Relating to Audion or Lamp Relays or Amplifying Apparatus, (for which I have filed applications in France April 15, 1916, and England April 16, 10 1917,) of which the following is a specification.

This invention relates to audions or thermionic relays or amplifiers for use for example in wireless telegraphy and telephony.

15 The object of the present invention is to determine the conditions of construction of the transformers utilized in these amplifiers for the purpose of obtaining the maximum relay effect given by the lamps; also to indicate the precautions to be taken in order to obviate objectionable noises.

I will describe with reference to the accompanying drawing various apparatus in accordance with this invention but I do not

25 limit myself to the precise arrangements and connections described and illustrated.

Figs. 1, 2 and 3 illustrate diagrammatically different embodiments of my invention.

30 Fig. 4 is a sectional view of a transformer forming part of my invention, and

Fig. 5 illustrates diagrammatically a modification of the embodiment shown in Fig. 3.

35 Fig. 6 illustrates a container for the transformer.

$$(1) (i - i_o) = \left(\frac{di}{dv} \right)_{v=v_o} (v - v_o) + \left(\frac{di}{dV} \right)_{V=V_o} (V - V_o)$$

The derivatives or ratios $\frac{di}{dv}$ and $\frac{di}{dV}$ can 75 be easily determined by experiment. They are given by the curve of the grid current as a function of v for a given potential V_o on the plate and by the curve of the grid current as a function of V for a given potential v_o in the grid. The inverse or reciprocal of these derivatives has the dimensions of a resistance. Thus:

$$\left(\frac{di}{dv} \right)_{v=v_o} = \frac{1}{r_1}$$

$$\left(\frac{di}{dV} \right)_{V=V_o} = \frac{1}{r_2}$$

$$(2) (I - I_o) = \left(\frac{dI}{dV} \right)_{V=V_o} (V - V_o) + \left(\frac{dI}{dv} \right)_{v=v_o} (v - v_o).$$

Referring to the drawing the thermionic relay 1, comprises a plate 2, a grid 3 and a filament 4 which may be rendered highly incandescent by a battery 5 (Figures 1 and 40 2). Between the plate and one terminal of the filament (the negative terminal for example) is connected a battery 6, either directly through a resistance 7 (Figure 1) or through the primary coil of a transformer 45 8 the secondary coil of which is connected with a resistance 7 as shown in Figure 2.

The grid and the filament are connected on the other hand, either directly or through the agency of a transformer, to the terminals of the source containing the small electro-motive force to be detected.

In the following description I have set forth the equations for the grid current and the plate current in the case of an infinitely 55 small alternating voltage introduced into the grid filament circuit. These equations are indispensable in order to rationally carry out the construction of the amplifiers with lamps.

The potentials V on the plate and v on the grid may be stated with relation to one terminal of the filament for example the negative terminal.

The current i in the grid is a function of v and of V . Thus $i = f(v, V)$.

At an operating point where the continuous potentials are v_o , V_o and corresponding to a continuous current i_o in the grid we have:

Under these conditions equation (1) can be written thus:

$$(1a) (i - i_o) = \frac{v - v_o}{r_1} + \frac{V - V_o}{r_2}$$

The current I in the plate is in its turn a function of V and of v . Thus $I = f(V, v)$. What has been said on the subject of current i may be repeated for I . At any point defined by the same continuous potentials V_o and v_o on the plate and on the grid and corresponding to a current I_o on the plate we have:

The derivatives or ratios $\frac{dI}{dV}$ and $\frac{dI}{dv}$ can be easily determined by experiment. They are given by the curve of the plate current as a function of V for a potential v_o on the grid and by the curve of the plate current as a function of v for a potential V_o on the plate.

The inverse or reciprocal of these derivatives or ratios has again the dimensions of a resistance.

Thus:

$$15 \quad \left(\frac{dI}{dV} \right) V = V_o = \frac{1}{r_s}; \quad \left(\frac{dI}{dv} \right) v = v_o = \frac{1}{r_4}$$

Equation (2) can be written under these circumstances as follows:

$$20 \quad (2a) \quad (I - I_o) = \frac{V - V_o}{r_s} + \frac{v - v_o}{r_4}$$

In variable order let us suppose that $(v - v_o)$ is an infinitely small alternating potential u , $(i - i_o)$ will become an alternating current j , $(V - V_o)$ an alternating potential U , $(I - I_o)$ an alternating current J , and we shall have for the lamp relay the equations

$$30 \quad (I) \quad \begin{cases} j = \frac{u}{r_1} + \frac{U}{r_2} \\ J = \frac{U}{r_3} + \frac{u}{r_4} \end{cases}$$

A fourth equation may be obtained by considering the outer or plate-filament circuit.

35 If a resistance R be interposed directly in the plate filament circuit, we shall have, denoting the voltage of the battery by E

$$E - IR = V$$

$$40 \quad \text{or} \quad E - (I - I_o)R - I_oR = (V - V_o) + V.$$

$$\text{or} \quad E - I_oR - V_o = U + JR$$

The first term is necessarily zero since for 45 the point of operation considered, we have, by hypothesis

$$E - I_oR = V.$$

We therefore arrive at the equation:

$$50 \quad U + JR = 0$$

If we suppose that the resistance R is inserted together with the insertion of a perfect transformer (i. e. one having no magnetizing current, and capacity of windings zero, no leakages and no losses) we arrive at the same equation. The fall of pressure caused by the transformer is, in effect, due to the circulation in the resistance R of an alternating current $K J$, denoting by K the ratio of transformation of the transformer in the step down direction.

We have therefore

$$65 \quad U + K^2 JR = 0$$

In the case of the transformer the only difference that exists is that the voltage E of the battery corresponds to the tension or voltage V_o at the plate.

By placing the resistance R in all cases 70 directly in the circuit of the lamp the fundamental equations for the lamp become:

$$75 \quad (II) \quad \begin{cases} j = \frac{u}{r_1} + \frac{U}{r_2} \\ J = \frac{U}{r_3} + \frac{u}{r_4} \\ U + JR = 0 \end{cases}$$

If the resistance R is purely non-inductive 80 the vectors j , u , U and J are necessarily in phase and the system of equation (II) corresponds to the following system:

$$85 \quad (III) \quad \begin{cases} j = \left[\frac{1}{r_1} - \frac{r_3 R}{r_2 r_4 (r_3 + R)} \right] u \\ U = - \frac{r_3 R}{r_4 (r_3 + R)} u \\ J = \frac{r_3}{r_4 (r_3 + R)} u \end{cases}$$

We shall call the relay-effect the ratio between the energy liberated in the plate filament circuit with a resistance R and the 95 energy furnished and consumed in the grid filament circuit. The relay effect corresponds to the ratio $\frac{UJ}{uj}$

It will be easily found that

$$100 \quad \frac{UJ}{uj} = r_1 \left(\frac{r_3}{r_4} \right)^2 \times \frac{R}{(r_3 + R) \left[(r_3 + R) - \frac{r_1 r_3}{r_2 r_4} R \right]}$$

There is a value of R which will be denoted by R optimum which gives a maximum value for the relay effect

Thus:

$$110 \quad R \text{ (optimum)} = \frac{r_3}{\sqrt{1 - \frac{r_1 r_3}{r_2 r_4}}}$$

If a transformer be employed such a 115 transformer should be chosen having a ratio of transformation K such that

$$120 \quad K^2 R = \frac{r_3}{\sqrt{1 - \frac{r_1 r_3}{r_2 r_4}}}$$

On the other hand it is found, by referring to equation (III) that the apparent resistance Y of the grid filament circuit is

$$125 \quad Y = r_1 \frac{(r_3 + R)}{(r_3 + R) - \frac{r_1 r_3}{r_2 r_4} R}$$

If the source which contains the tension or voltage u has an impedance Z it will be nec- 130

essary to employ, in order to supply the grid-filament circuit, a transformer the transformation ratio of which in the step up direction will be such that

$$K^2 Z = Y = r_1 \frac{r_3 + R}{(r_3 + R) - \frac{r_1 r_3 R}{r_2 r_4}}$$

- 10 In this way the maximum power can be obtained from the source. Care will have to be taken that the capacity of the secondary winding of the transformer be such that, for the frequency of current considered, it does 15 not tend to short circuit this winding by closing it across a capacity smaller than Y . It is supposed in the foregoing description that the capacity represents an impedance considerably greater than Y .
- 20 We have thus determined with precision the ratios of transformation to be adopted in transformers as used for thermionic relays.

With regard to the constitution of the 25 transformers themselves the theoretical conditions above indicated will be approached.

- (1) By using a sufficient mass of iron and sheets of high permeability for the reduction of the magnetizing current.
- 30 (2) By inserting the primary and secondary windings one in the other (for example by using a primary coil enclosed half way in the secondary winding or conversely) so as to reduce leakages.
- 35 (3) By using sheets of silicon of reduced thickness or of iron melted in vacuo for the reduction of losses.
- (4) By reducing the capacity of the windings with relation to the mass.
- 40 (5) By reducing the distributed capacity of the winding by causing the product of the resistance and of the capacity per unit of length of the wires forming the primary and secondary windings to be as small as 45 possible.

The object of the last precaution is to avoid the distortion of the word when a telephonic amplifier is employed.

In the case of high frequency currents the 50 primary and secondary coils may be formed of a plurality of successive layers several millimetres apart for the purpose of reducing the capacity between the layers. Coils in several strata will thus be obtained. Each 55 stratum may consist of two layers of similar wire arranged in parallel to reduce the resistance of the winding without increasing its capacity.

Figure 4 shows one of the forms that may 60 be adopted for the construction of the transformers. In this form, as will be seen, the magnetic circuit adopted comprises three branches: a middle branch around which are placed the primary and secondary coils, and 65 two side branches through which the flux

returns. This form of magnetic circuit is well known, but usually the cross section of the iron of the magnetic circuit at b and c , being designed to allow half the flux to pass therethrough, is only equal to about half the 70 cross section of the magnetic circuit at a . But the cross sections of the magnetic circuit at b and c may be made as great as the cross section at a , or even greater, so as to reduce as far as possible the value of the 75 induction in the parts of the magnetic circuit external to the coil. By this the losses are considerably reduced: they substantially no longer occur except in the part of the magnetic circuit located inside the windings. 80 The shape of the transformer thus becomes somewhat unusual. The quality of plates employed is of course that which gives the minimum losses by Foucault currents and hysteresis. The manner in which the windings are arranged has also been illustrated 85 in the figure. The primary is represented by the coil Y sandwiched between the coils X and Z which constitute the secondary winding, the coils X and Z being connected 90 in series. In this way the magnetic leakage between the primary and secondary is greatly reduced. A suitable distance e is left between the windings and the magnetic circuit in order to reduce the capacity between this 95 circuit and the windings.

In equation (2) it has been first supposed that the resistance R was non-inductive but it may be imagined that R represents in general any impedance whatsoever and the equations may be solved by imaginary quantities by treating u , j , V and J as vectors capable of a certain displacement of phase between them. This case corresponds to that in which the apparatus is provided for example with 100 a telephone receiver.

The working resistance above considered may obviously be constituted by the grid filament circuit of a second lamp which will act in its turn on the working resistance R 110 proper.

This is shown in Figure 3 in which the same battery P is utilized for the two lamp relays. The use of three transformers T_1 , T_2 , T_3 is then necessary.

The ratio of the first transformer is determined by the value of the impedance Z of the source of current having the voltage u . The ratio of the transformer T_2 is determined by the value of R optimum and of Y . $K^2 R$ 120 optimum will be made equal to Y .

It will be noted that the utilization of one and the same battery is effected without complications of a special kind according to the arrangement shown in Figure 3, with the 125 proviso that the resistance of the battery be negligible.

The source which supplies the transformer T_1 may be a circuit comprising a battery and a microphone and an amplification may 130

be obtained from the transmitting end. In this case as there can be no longer any question of an infinitely small voltage u , but of an appreciable voltage $e \sin \omega t$ the 5 resistance Y of the grid filament circuit can only be interpreted as a mean resistance resulting from a mean value of v between $(v_0 - e)$ and $(v_0 + e)$. In practice it happens 10 that $\frac{di}{dv}$ rapidly becomes zero for v negative if $v_0 = 0$. In this latter case the mean obtained will therefore be the double of the mean for the time during which v remains positive, which mean can be easily appreciated by the curve of the grid current. This mean being determined the reciprocal thereof will be taken to determine the resistance r_1 .

In reality it is convenient to take account 20 of the harmonic developed by the variable character of r_1 . Distortion might result therefrom. This will be reduced by keeping within the bounds of a lower ratio of transformation for the transformer T_1 . For 25 the purposes of speech, what will be lost in intensity will be gained in clearness.

It is known that the weakening in intensity of an alternating current that is being transmitted along a telephone line is 30 greater according as the frequency of the current is higher. It is for this reason that in telephone lines of a certain length the high-frequency harmonics of the telephone current are absorbed by the line. There 35 results from this a distortion of speech at the receiving end. This distortion may be counterbalanced by promoting the amplification of these harmonics at the transmitting end and at the receiving end.

40 It is possible in an amplification at the transmitting end to seek to forestall the deformation introduced by the telephonic line by setting up in anticipation a deformation in the opposite direction by artificial arrangements in the primary circuit of the transformer T_1 . An elementary arrangement consists in shunting for example the primary coils of the transformers by a self induction or choke-coil or by constructing 45 these transformers with a heavy magnetizing current. In this way the high frequency currents will be favoured relatively to those of low frequency which will tend to be short circuited; the harmonics will stand 50 out better and the damping action of the line will have a less injurious effect.

It is possible, in an amplification at the receiving end to attempt in like manner to 60 restore the form of the word and to neutralize the distorting action of the line. An elementary arrangement would again be to supply the primary coil of the transformer T_1 with the insertion of a small capacity which would allow preference of passage to 65 currents of higher frequency or harmonics.

The arrangement of the capacity may extend to all the transformers in succession. In place of a capacity a "damper" may be employed (composed of a self induction coil and a capacity in shunt) which will be 70 obtained by having a greater impedance for the low frequencies.

Arrangements of this kind are illustrated by way of example in Fig. 5, in which the connections are similar to those shown in 75 Fig. 3, the modifications referred to above consisting in the insertion of small capacities 9 in the circuits supplying current to the transformers T_1 and T_2 , respectively. Either or both of these capacities may be shunted 80 by a self-induction coil tuned so as to have a greater impedance for low frequencies, one such coil being shown at 11 in the circuit connected to the transformer T_2 .

In any way it can be seen that by an 85 amplification at the outset and at the receiving end it is possible to compensate the distortion introduced by the transmitting line.

The same apparatus shown in Figure 3 90 may serve for amplification at the transmitting end and for amplification at the receiving end by the action of a simple commutator which will substitute the line circuit for the microphonic circuit and the 95 telephone circuit for the line circuit. The microphonic circuit might utilize as a battery the local battery used for heating the filament or a battery P . In the receiving position the current will be cut upon the microphone.

It is possible also while transmitting and receiving to change, if necessary or desired, the ratios of transformation of the 100 transformers T_1 and T_2 .

A similar apparatus would allow each subscriber of a telephonic system to effect communication individually a long distance away.

In order to reduce the relative importance 110 of the disturbing currents a high resistance may be used which would restore the audibility of the word to a normal value by considerably reducing the superfluous noises.

115 A particular phenomenon which is produced in the thermionic relays is that of "singing" or "howling" due to static phenomena. This may be prevented by properly defining the potential of the cores of the transformers and if necessary, that of their 120 windings as well as that of the primary coil of the transformer T_1 with relation to the battery P . To this end, it suffices to connect the above mentioned masses which may be represented by M_1, M_2, M_3 and a primary terminal of the transformer T_1 to any point of the battery P , either to the positive pole or to the negative pole or to an intermediate cell as shown in dot and dash lines in Figure 3.

125 In the particular case in which the work- 130

ing resistance R is a telephone receiver and in which it is desired to avoid too great a difference of potential between the winding of the telephone and the mass, the potential 5 of the positive pole of the battery will be chosen as the potential of the mass.

In like manner the core of the windings of the transformers (always more particularly of the transformer T_1) might have its potential defined. 10

It might be found advantageous in certain cases to arrange the transformers in conductive casings (see Fig. 6) such as copper or aluminum by the known method of Faraday's cage in order to avoid magnetic leakage from one transformer to the other and at the same time to define their static potential. This arrangement will be particularly interesting in the case of the aperiodic reception 15 at high frequency.

This remark refers to the case in which, in conformity with what is provided by the invention, there is established for reception in wireless telegraphy an amplification of the 25 high frequency current received by the antenna by means of iron transformers as it were a matter of a low-frequency current. In this case one can refrain from establishing special syntony with capacity on the primary 30 or secondary circuit of above mentioned transformers for the frequency of the current received which eliminates the adjustments in the amplifying system.

Having fully described my invention, what 35 I claim as new and desire to secure by Letters Patent, is:

1. In an amplifying apparatus for wireless signals and the like, a thermionic relay comprising an evacuated bulb, a plate, a filament and a grid in said bulb, and a transformer having a core of laminated iron and two windings of relatively low capacity arranged coaxially one to the other, one of said windings being in circuit with said plate 40 and filament, the transformation ratio of said transformer being a function of the value of the imaginary impedance which, if inserted in the plate filament circuit, would give rise to the maximum relay effect.

50 2. In an amplifying apparatus for wireless signals and the like, a thermionic relay comprising an evacuated bulb, a plate, a filament and a grid in said bulb, and a transformer having a core of laminated iron and two windings of relatively low capacity arranged coaxially one to the other, one of said windings being in circuit with said grid and filament, the transformation ratio of said transformer being a function of the value of 55 the imaginary impedance which, if inserted in the grid filament circuit, would give rise to the maximum relay effect.

3. In an amplifying apparatus for wireless signals and the like, a thermionic relay 60 comprising an evacuated bulb, two electrodes

and a conducting body in said bulb, an external circuit between said electrodes, an external circuit between said conducting body and one of said electrodes, and a transformer having a laminated iron core and two windings of relatively low capacity arranged coaxially one to the other and comprising each a plurality of layers of conductors connected in parallel, one of said windings being inserted in one of said circuits, the transformation ratio of said transformer being a function of the value of the imaginary impedance which, if inserted in the latter circuit, would give rise to the maximum relay effect. 70

4. In an amplifying apparatus for wireless signals and the like, a thermionic relay, a transformer having a winding connected therewith, a magnetic metal core for said transformer, and means for defining the potential of said core. 80

5. In an amplifying apparatus for wireless signals and the like, a thermionic relay, a transformer having a winding in circuit therewith, a magnetic metal core for said transformer, and means for defining the potential at one point of the winding of said transformer which is not in circuit with said relay. 90

6. In an amplifying apparatus for wireless signals and the like, a thermionic relay, a transformer having a winding connected therewith, a magnetic metal core for said transformer, a source of current, and a connection between said metal core and source 100 of current. 95

7. In an amplifying apparatus for wireless signals and the like, a thermionic relay, a transformer, a magnetic metal core for said transformer, and a source of current 105 connected with said relay, one winding of said transformer being in circuit with said relay, the other winding of said transformer being connected with said source of current, and the core of said transformer being connected with said source of current. 110

8. In an amplifying apparatus for wireless signals and the like, a thermionic relay comprising an evacuated bulb, a plate, a filament and a grid in said bulb, a transformer, a magnetic metal core for said transformer, a source of current, said source of current and one winding of said transformer being in circuit with said plate and filament, and a connection between said core 115 and one terminal of said source of current. 120

9. In an amplifying apparatus for wireless signals and the like, a thermionic relay comprising an evacuated bulb, a plate, a filament and a grid in said bulb, a transformer, a magnetic metal core for said transformer, one winding of said transformer being in circuit with said filament and grid, a source of current in circuit with said plate and filament, and a connection 125 130

6
between said core and one terminal of said source of current.

10. In an amplifying apparatus for wireless signals and the like, a plurality of 5 thermionic relays comprising each an evacuated bulb, a plate, a filament and a grid in said bulb, transformers having one of their windings in circuit with the filament and grid of each of said lamps respectively, a 10 magnetic metal core for each of said transformers, a common source of current in circuit with the plate and filament of each of said relays, and connections between said source of current and the core of each of 15 said transformers.

11. In an amplifying apparatus for wireless signals and the like, a plurality of thermionic relays comprising each an evacuated bulb, a plate, a filament and a grid in 20 said bulb, transformers having one of their windings in circuit with the filament and grid of each of said lamps respectively, the other winding of one of said transformers being adapted to be connected to a source of 25 potential, a common source of current in circuit with the plate and filament of each of said relays, and a connection between said source of current and the transformer winding adapted to be connected to a source 30 of potential.

12. In an amplifying apparatus for wireless signals and the like, a thermionic relay, a transformer having two windings arranged one within the other and an iron 35 core therefor, one of said windings being in circuit with said relay, said transformer being adapted to operate with high frequency currents.

13. In an amplifying apparatus for wireless signals and the like, a thermionic relay, a transformer having one winding in circuit with said relay, and an iron core therefor, said core comprising two side branches 40 and a central branch connected at their ends, the two windings of the transformer being 45 arranged one within the other and around

the central branch of the core, the cross sectional area of each of the side branches being at least equal to that of the central branch.

50

14. In an amplifying apparatus for wireless signals and the like according to claim 1, means whereby the transformer provides a deformation of a telephone current in opposition to the deformation provided by the 55 line, to promote the amplification of the high frequency currents in telephonic transmission, and correct the distortion of speech at the receiving end.

15. In an amplifying apparatus according 60 to claim 1, for the telephonic transmission of wireless signals and the like, a thermionic relay having means for promoting the amplification of the high frequency harmonics at the transmitting end, to counter-balance 65 the distortion of speech due to the weakening in intensity of the alternating current.

16. In an amplifying apparatus for the telephonic transmission of wireless signals and the like, a thermionic relay in which a 70 transformer has means for neutralizing the distorting action of the line by an amplification of the high-frequency harmonics of the telephone current and for counter-balancing the distortion of speech at the receiv- 75 ing end.

17. In an amplifying apparatus for wireless signals and the like, a thermionic relay, a transformer having two windings arranged coaxially one to the other, an iron 80 core therefor one of said windings being in circuit with said relay, and a conductive casing for said transformer in order to avoid magnetic leakage and to define the static potential of the transformer. 85

In testimony whereof I affix my signature in presence of two witnesses.
